UNITED STATES PATENT OFFICE.

FRANK M. LEAVITT, OF BROOKLYN, NEW YORK, ASSIGNOR TO THE
E. W. BLISS COMPANY, OF SAME PLACE.

POWER-SHEARS.

SPECIFICATION forming part of Letters Patent No. 577,107, dated February 16, 1897.

Application filed April 2, 1894. Renewed July 13, 1896. Serial No. 599,058. (No model.)

To all whom it may concern:

Be it known that I, FRANK M. LEAVITT, a citizen of the United States, residing in Brooklyn, in the county of Kings and State of New York, have invented certain new and useful Improvements in Power-Shears, of which the following is a specification.

This invention relates to shears for cutting heavy bars off into lengths, being especially designed as a muck-bar shears.

The invention provides means for making the operation automatic, the muck-bar or other bar or thing to be cut up being fed between the shearing-jaws, and the jaws tripped and caused to operate upon a predetermined length of bar having been fed through, so that the bar is cut up into pieces of uniform length.

The invention provides several improvements relating to the control of such shears for starting and stopping the same and operating the shearing-jaws automatically or by hand, as may be required, all as will be hereinafter set forth.

In the accompanying drawings, which illustrate the preferred embodiment of my invention, Figure 1 is a front elevation of the machine. Fig. 2 is a front view of the head carrying the upper or movable shearing-jaw with the front plate detached. Fig. 3 is an elevation of the right-hand side of the machine, the roller-table for feeding the bar being in transverse section on the line 3 3 in Fig. 1. Fig. 4 is an elevation of the left-hand side of the machine. Fig. 5 is a sectional fragmentary view of a portion of the mechanism shown in Fig. 4 isolated from the remaining parts to show its construction more clearly. Fig. 6 is a fragmentary plan, partly in horizontal section, on the line 6 6 in Fig. 4. Fig. 7 is a plan of the sliding receiving-table shown in Fig. 6 removed. Fig. 8 is a plan of the movable guide-bar and clamp seen in Fig. 6 removed. Fig. 9 is an end or front view of the clamp shown in Fig. 8. Fig. 10 is a section through the roller-table and shears on the line 10 10 in Fig. 6. Fig. 11 is a front view in section, showing the clutch and clutch-operating mechanism isolated from the remainder of the machine. Figs. 12 and 13 are transverse sections through the roller-table,

taken, respectively, on the lines 12 and 13 in Fig. 10. Fig. 14 is a sectional plan view showing a portion of the mechanism in detail, Fig. 14^a is a fragmentary plan of the slide-bar shown in Fig. 14, and Fig. 14^b is a fragmentary front view of the same bar. Fig. 15 is a transverse section on the line 15 15 in Figs. 1 and 6. Fig. 16 is a fragmentary sectional front view, partly in section, on the line 16 16 in Fig. 15 and showing the shears closed. Figs. 10 and 12 to 16 are on double the scale of the remaining figures.

I will now proceed to describe the preferred construction of my machine with reference to the said drawings.

The main frame A of the shears is of usual construction, being a heavy massive frame of great strength and formed with a recess, as usual, in which the shearing-jaws operate, being formed beneath this recess with a fixed jaw A' for the lower or fixed shear, and with a head A², Fig. 4, in which slides the frame carrying the upper or movable shear, and being formed to support the shear-operating shafts, gearing, and other accessory parts. The lower or fixed shear is lettered a, and the upper or movable shear is lettered b, the latter being carried by the movable jaw B, which is constructed as a slide moving vertically in ways in the head A², as shown in Fig. 2. It is driven by an eccentric c, working in a sliding block c' and formed on the end of the shear-operating shaft C, which shaft is shown in dotted lines in Fig. 3, and has bearings in the main frame A. On the opposite end of this shaft is fixed a large gear-wheel C', which meshes with a driving-pinion D', fixed to the drum D of a clutch, these parts D D' being loosely mounted on the driving-shaft E, which is driven continuously by any suitable power. For driving it I have shown a steam-engine F, mounted on the main frame A, its pitman engaging a crank E', Fig. 3, on the shaft E. This shaft is hung in suitable bearings and has fixed on it preferably a fly-wheel e, and also the driving member of a clutch G, of which clutch the drum D constitutes the driven member. The particular construction of the clutch is immaterial, several clutches being known to machinists that will answer the purpose of coupling the driving-shaft E

to the pinion D', which is the essential function of this clutch. Normally the shaft E revolves idly, carrying the driving member of the clutch around with it; but when the clutch 5 is operated to engage the drum D the latter and the pinion D' are revolved with the shaft E, thereby imparting motion to the gear C' and shaft C, and consequently operating the shear-jaw B to cause the upper shear to descend and make its shearing cut and then to re-ascend to its normal position. (Shown in Fig. 2.) Upon reaching this position the clutch G automatically disengages itself, thereby stopping the jaw in position ready for the next 5 shearing operation.

It is thus essential that the operating-shaft C be driven one revolution at a time whenever a shearing cut is required to be made, and stopped at the end of the revolution. To 10 perform this service, I have adopted and applied in the construction of my present machine the clutch mechanism for power-presses, &c., claimed in my Patent No. 490,715, dated January 31, 1893, as will be seen by comparing Fig. 11 of my present application with Fig. 4 of that patent, only slight changes in the arrangement of the parts having been made, with some improvements in details of construction, which I will presently describe. 15 I will here briefly describe the mechanism, referring the public to my said patent for a more complete understanding of its essential features.

Fixed on the operating-shaft C is a cam d, 20 operating on a lever d', at the free end of which is jointed a sleeve d'', to which is pivoted a trip-lever or pawl j, which engages a notch in an upright rod K and normally upholds it until tripped by the rocking of an 25 elbow-lever Q, which is rocked by pulling down a rod m, Fig. 11. When thus tripped, the rod K falls, its weight being increased by a heavy block K', fixed to it, and its fall being eased by dash-pot K''. As the block descends 30 it rocks an elbow-lever J from the position shown in full lines in Fig. 5 to that shown in dotted lines, and as the upright arm of this lever engages a slot in a sliding bar II it slides 35 this bar to the right in Fig. 5, this bar sliding 40 in a frame H', Fig. 4, which also forms a bearing for the shaft of lever J. The bar II carries an arm f, which in so moving slides the controlling-hub G' of the clutch G toward the drum D, and thereby causes the gripping- 45 jaws rr of the clutch to close upon and clamp the drum D, so that it is driven with the clutch. I will not describe the details of this clutch, as the same are immaterial to my present invention and are fully disclosed in 50 my said patent. By the same movement a brake which normally holds the drum D from revolving is released. The construction and operation of this brake are somewhat different from that in my said patent. The brake 55 consists of two jaws g g, Fig. 11, pivoted together and to the frame H' at g' and carrying nuts h h' engaged, respectively, by right and

left hand screw-threads on an oscillatory shaft h, so that when this shaft is oscillated in one direction the jaws are moved apart, 70 and in the other direction are drawn together. The jaws carry brake-shoes i i, which as they are drawn together bear against the outer and inner sides of the rim of the drum D. When the rod K is elevated, the jaws are 75 drawn together and the brake-shoes pressed against the rim to clamp it and hold the drum stationary, but as the rod K falls a lever-arm i', engaged by a block K' and fixed on the shaft h, is moved from the position shown in 80 full lines in Fig. 5 to that shown in dotted lines, thereby oscillating the shaft h, and by the action of the right and left threads on the nuts the jaws g are thrust apart and the brake-shoes released, thereby freeing the 85 drum. It results from these constructions, that upon pulling down the rod m and tripping the pawl j the brake holding the drum D is released and the clutch is instantly applied to drive it, so that the shaft C is driven 90 in the direction of the arrow in Fig. 11. Before the end of one revolution of this shaft the cam d drops the lever d' to enable the pawl j to reengage with the notch in the rod K, and just before the end of the revolution 95 is completed the cam lifts the lever, and thereby through the sleeve and pawl lifts the rod K to its normal position. In so doing the opposite movements are transmitted to the clutch and brake in order to release the clutch 100 and reengage the brake to check the momentum of the parts and stop the shaft, the stoppage of the latter occurring at the end of one revolution.

An improvement in detail over the construction shown in my aforesaid patent consists in the means for connecting the rod K with the levers J and i' through the medium of the block K'. This block has two transverse slots cut through it or into it, into which 105 the said levers project, their ends being rounded, as shown in Fig. 5, and seated in rounded sockets in sliding blocks l l', respectively, which blocks fit the transverse slots, so as to slide in said slots and allow for the movement 110 of the ends of the levers in the arcs of circles. 115

The means for operating the shears from the driving-shaft and for coupling and uncoupling the clutch having now been made clear, I will proceed to describe the other and 120 more novel features of my improved machine.

My improved shears being designed most particularly for cutting up muck-bars as they come hot from the muck-rolls, it is important that means shall be provided for feeding the 125 muck-bar to the shears. To this end I provide a roller-table which as a whole is lettered L, being seen on the right of the shears in Figs. 1, 6, and 10. Only a portion of this roller-table is shown, it being of variable 130 length, according to circumstances, and extending from the muck-rolls to the shears, so that as the bar emerges from the rolls it runs onto the table and is carried along thereby to 135

the shears. The roller-table should consequently be longer than the length of the muck-bar. It is made up of rollers k k , arranged on horizontal axes at suitable intervals apart and driven in the same direction at a uniform speed, the upper sides of the rollers turning toward the shears, as denoted by the arrows in Figs. 6 and 10, so that they feed or carry the bar to the shears. The rollers are supported on a frame L' , of any suitable construction, one end of which is connected to the main frame A. This frame L' is shown as consisting of longitudinal side bars or plates, with transverse webs at intervals, the side bars being formed at their upper sides with the necessary bearings for supporting the journals of the rollers. The rollers are driven from the main driving-shaft or crank-shaft E of the engine by means of a pinion e' , formed on the end thereof, Figs. 3, 6, and 10, meshing with a gear e^2 , fixed on the shaft of the next to the end roller. On this shaft is also fixed a gear-wheel f' , meshing with an idler-gear f^2 , Fig. 10, which drives a gear f^3 on the shaft of the next roller to the right, and from this shaft, by miter-gears m' , rotation is transmitted to a longitudinal shaft M, extending thence to the right and from which all of the remaining rollers k k are driven by pairs of miter-gears, as shown in Fig. 6. The terminal roller k' is driven from the gear-wheel f' through the medium of an idler-gear f^4 , meshing with a gear on the roller-shaft, and this same idler-gear f^4 communicates motion to an upper feeding-roller n by meshing with a gear-wheel n' , Fig. 10, which in turn drives the gear-wheel n^2 and the roller n . This upper roller n in connection with the roller k' serves for more positively feeding the muck-bar to the shears than by its mere resting on the roller-table, since the roller n is pressed downwardly against the top of the bar, so that the bar is pinched between the two rollers, which, revolving in opposite directions, act in the same direction to thrust the bar toward the shears.

For pressing down the roller n I provide a weight w , Fig. 1, mounted on the end of a lever w' and pulling down through a link or bar w^2 , the upper end of which is connected to the shaft of roller n or to the frame which carries this roller. To admit of the roller n being moved up or down while continuing its rotation, it is mounted in the arms of a frame o , which is pivoted on the same axis as the gear n' , preferably by being formed with a tubular elongated hub o' , which is mounted on a shaft o^2 , either stationary or revolving, on which the gear n' is also mounted, and which shaft is supported above the frame L' . Hence by the swinging of this frame o the roller n may be raised or lowered, being constantly pressed down by the tension of the weight w .

65 For guiding the muck-bar as it is carried along by the roller-table opposite guiding strips or bars p and p' , Fig. 6, are provided,

being mounted just above the tops of the rollers, so as to engage the side edges of the muck-bar. The bar p' is preferably fixed in position, although it might be adjustable, and the adjustment to accommodate muck-bars of different widths is preferably made by moving the bar p toward or from the fixed bar. To this end this bar is mounted at intervals on brackets p^2 , Figs. 1 and 6, which brackets may slide laterally along dovetail or undercut grooves p^3 , Fig. 10, in the cross-bars of the supporting-frame L' and being clamped to said grooves by headed bolts in an ordinary manner.

The roller-table is provided with means for gripping or clamping the muck-bar when desired to arrest its forward feed to the shears. To this end I provide a clamp adapted to grasp the muck-bar on opposite sides and grip it so firmly that the mere forward impulse of the rollers k , on which it rests, will be insufficient to propel it forward. This clamp as a whole is lettered I, and consists of a fixed jaw I' on one side and a movable jaw I^2 on the other side of the muck-bar. Both jaws might be movable simultaneously toward and from each other, but it is preferable to make the jaw I' stationary and form it as a reinforced or strengthened continuation of the guide-bar p . The movable jaw I^2 (shown detached in Figs. 8 and 9) consists of an upright wall mounted on a slide s , which in the construction shown is formed as a saddle seated and sliding on the top of the transverse partition L^2 of the frame L' . (See Fig. 10.) The slide thus moves with a parallel motion transversely of the roller-table, and its clamp I^2 is kept parallel with the fixed jaw I' . For moving the jaw I^2 a rod s' is connected to the slide s and passes off to the front of the machine, as shown in Figs. 6 and 13, where its end is connected to a crank-arm s^2 on a rock-shaft N' , to which is fixed an operating handle or lever N , so that by pressing down this handle the rod s' is pulled to close the clamp upon the muck-bar. At the same instant that the bar is thus gripped it is important that it should be freed from the tractive strain due to its being pinched between the feed-rollers n and k' . To this end I provide for lifting the roller n simultaneously with the closing of the clamp. To do this, I fix on the rock-shaft N' a cam-arm N^2 , Fig. 12, which acts against an adjusting-screw seated in a boss w^3 on the upright bar w^2 and which is connected to the frame o of the roller n , thereby lifting the frame and roller as the lever N is pressed down. Thus the roller n is lifted off the muck-bar just before the bar is gripped by the clamp, the one downward movement of the handle N serving to accomplish both movements and thereby arrest the feed of the muck-bar. When the handle is released, the weight w restores the parts to their normal position.

As the clamping-jaw I^2 has a parallel motion it is necessary to provide for guiding

the muck-bar so that it shall pass between this jaw and the fixed jaw I^2 . To this end I provide a swinging guide-bar P , Figs. 6 and 8, pivoted to the frame at p^4 in line with the fixed guide p^1 , and jointed near its other end to the clamping-jaw I^2 in order to move out and in with it and form thereby an inclined guide for directing the muck-bar between the clamping-jaws whatever may be the position of the jaw I^2 . To effect their connection, the jaw I^2 is provided with an upwardly-projecting pin s^3 , Figs. 8 and 9, which enters an elongated hole or slot s^4 in the bar P , and to better connect the parts I^2 and P the former is made with a flat plate or extension j' and the latter with an extended nose j^2 , which lies over said plate, as shown in Figs. 8 and 13. To prevent any lifting or tilting of the muck-bar while under the action of the shears, and particularly of the last end of the bar when it has passed beyond the rollers $n^1 k^1$, I provide a bridge q , under which the bar passes on its way to the shears, Fig. 10.

In order to render the shearing operation automatic, so as to cut the muck-bar off into sections of uniform length, I provide the clutch-tripping mechanism which I will now describe. The end of the muck-bar as it is fed through between the open jaws of the shears strikes against a push-plate R , which is so mounted that it is movable, yielding to the push or thrust exerted by the end of the muck-bar as it feeds forward. In the construction shown the push-plate is fixed on a plunger R' , which slides freely in a fixed head-block S , a parallel guide-rod r' serving to hold it from tilting. Against the rear end of the plunger R' comes the end of a push-rod R^2 , as best shown in Fig. 14. This rod passes through a block t' , in which it is fixed by a set-screw, and this block is pivoted to one arm of a lever t , the opposite arm of which is jointed, as shown in Fig. 6, to a push-rod m^2 , the opposite end of which is jointed to one arm of an elbow-lever u , Fig. 11, the oscillating shaft u' of which extends from front to rear along the frame A and the opposite arm of which is jointed to the pull-rod m , previously described. A spring m^3 is connected to the elbow-lever u , Figs. 1 and 11, to exert a retractile thrust against the rods m m^2 R^2 . When the push-plate R is pushed back by the muck-bar striking it, this thrust is communicated through the rods R^2 , m^2 , and m in the direction of the arrows, pulling down the latter and rocking the elbow-lever Q to trip the pawl j , and thereby engage the clutch and cause the operating-shaft C to execute one revolution, as before described, so that the shears are operated to cut off a length from the muck-bar. The length thus cut off drops out of the way, and as the shear-jaw B rises the muck-bar again feeds through between the shears and the operation is repeated.

In order to enable the automatic trip-motion for the clutch thus described to be thrown out of gear or rendered inoperative when de-

sired, a lever T is provided, pivoted on the head-block S , Fig. 6, and having an arm extended downward, Fig. 15, and formed with a hole through which the rod R^2 passes freely, Fig. 14, so that the rod may slide through this hole as it is pushed by the plunger R' , but by throwing the lever T to either side this end of the rod R^2 is swung laterally far enough to stand clear of the plunger R' , so that when the push-plate is thrust back by the muck-bar its movement is not communicated to the rod R^2 and the clutch is not operated. When the automatic trip is thus thrown out of action, it is necessary to have some means for tripping the clutch by hand. To this end I provide a clutch-operating lever U , Fig. 1, fixed on a rock-shaft U' , Fig. 4, on the rear end of which is fixed a lever-arm U^2 , Fig. 11, the free end of which comes against the elbow-lever Q , so that by pulling down on the lever U the lever Q is operated to trip the pawl j to the same effect as if operated from the push-plate R . The lever U is retracted by a spring m^4 , which holds it normally out of action.

In order to render the automatic clutch-tripping mechanism adjustable to cut the muck-bar into different lengths, the head-block S is attached to a longitudinal bar S' , extending parallel to the direction of feed of the muck-bar, the block S having a sliding connection with the bar S' , so that it may be slid along this bar and set thereon by set-screws u^2 at any desired position. The rod R^2 has to be adjusted to the same extent, to provide for which it has a sliding connection with the block t' , to which it may be set in any position by the set-screw.

After the muck-bar begins to push the plate R and trips the clutch it continues to feed forward until the push-plate strikes the fixed block S , which stops the bar, which thus remains stationary while the shears cut it off. If the block S were immovable, the section of bar when cut off would be wedged tightly between the fixed shear and this block and be prevented from falling freely out of the way. To avoid this, the head-block S is so mounted that after the shear begins to operate on the bar the head-block moves away from the muck-bar, carrying the plate R with it, so as to leave the cut-off section free from end pressure. To this end the bar S' , to which the head-block is adjustably attached, is mounted, so as to slide longitudinally, being supported at its opposite ends in bearings q^2 , Fig. 14, and in order to impart the required motion to it it has a cam connection with the movable shear frame or jaw B . To effect this connection, the bar S' is formed with an oblique notch or recess S^2 , as shown in Figs. 14^a and 14^b, and this recess is engaged by an oblique arm J' , fixed to and projecting downwardly from the shear-jaw B . The obliquity of this arm is such that as the shear descends it thrusts the slide-bar S' to the left in Figs. 1, 14, and 16, so that the plate R re-

cedes from the muck-bar after the latter is caught by the descending shear. Fig. 16 shows the machine in the position where a section x' of the muck-bar x has just been severed by the shears and is about to fall.

In case the muck-bar has to be cut off into sections of considerable length it is desirable that some means shall be provided for supporting the end of the muck-bar that has been fed through to the shears before it is cut off in order to prevent its being bent or distorted by sagging under its own weight. To this end I provide a table V, (shown detached in Fig. 7,) which stands beneath the head S and push-plate R and in such position as to receive upon it the sagging unsupported end of the muck-bar as the latter is fed beyond the shears. Thus any length of muck-bar may be fed through before being cut off and it will be properly supported by this table. In order, however, to enable the cut-off section to fall out of the way as soon as it has been severed, I construct the table V to slide laterally, so as to pass out from under the muck-bar and cause the latter to drop. This sliding motion is effected simultaneously with the cutting movement of the shears and preferably by a mechanical connection with the shear-jaw B. As shown, this connection consists of a sort of elbow-lever constituted by a rock-shaft V', hung in suitable fixed bearings having downwardly-projecting arms V², the rounded ends of which engage slots v v in the table and having an arm V³, carrying a roller v', which is engaged by a slot v², formed on the shear jaw or frame B in the manner shown in Fig. 15. There being two arms V² engaging the table V, the latter is given a parallel movement sliding in transverse ways formed in the supporting frame or bracket A⁴ beneath it.

The operation of my improved muck-bar shears is as follows: The muck-bar as it comes from the rolls is directed onto the roller-table L, by which it is carried toward the shears. As the advancing end of the bar approaches the shears the operator presses down the handle N, so as to grip the bar by the clamp I in order to control its feed, releasing it and letting it feed forward little by little until the rounded advancing end of the bar has entered between the shears sufficiently far to cut off the rounded portion and form a square end on the first section or length to be cut from the muck-bar. He holds it in this position by holding down the lever N while he pulls the lever U to trip the clutch and make the shearing cut. He then releases both levers and permits the machine to operate automatically, the head S having been previously set to the required distance from the shears for cutting the sections of muck-bar to the proper length. As the end of the bar is fed through between the shears and strikes the push-plate R it trips the clutch, the shear descends and cuts off the bar, while at the same time the head S and plate R recede

from the end of the bar and the table V slides out from underneath it, thereby leaving it free to fall and causing it to drop down beneath the shears.

It must not be inferred from the particularity of detail with which I have illustrated and described the preferred construction of my improved machine that my invention is necessarily limited to the mechanical details thus set forth, since, in fact, it is susceptible of considerable modification in mechanical construction, and by the substitution of mechanical equivalents for the several instrumentalities shown, and by the omission or addition of certain parts as may be required for adapting it to varying purposes. Those features of my invention which are believed to be essential are sought to be defined in the claims.

I claim as my invention the following-defined novel features, substantially as hereinbefore specified, namely:

1. In a power-shears, the combination of a driving-shaft, a feed mechanism for the bar to be sheared, driven thereby, the movable shearing-jaw, a shear-operating shaft, driven from said driving-shaft, a clutch for coupling said shear-operating shaft to the driving-shaft to operate the shear, and a push-plate in the path of feed of the bar, connected to said clutch to engage the latter when displaced by the bar, whereby the shear is tripped automatically to cut off the bar into equal lengths.

2. In a power-shears, the combination of a driving-shaft, a clutch for coupling the movable shear to said shaft, a push-plate R in the path of feed of the bar being operated on, a head-block S supporting said push-plate, and mechanical connections between said push-plate and the clutch for engaging the latter when the push-plate is displaced by the bar.

3. In a power-shears, the combination of a driving-shaft, a clutch for coupling the movable shear to said shaft, a head-block S adjustable longitudinally of the direction of feed, with means for locking it in any adjustment, a push-plate carried by said block and movable relatively thereto arranged in the path of feed of the bar, and mechanical connections between said push-plate and clutch adapted to engage the latter when the plate is displaced by the bar.

4. In a power-shears, the combination of a driving-shaft, a clutch for coupling the movable shear to said shaft, and a push-plate in the path of feed of the bar being operated upon, connected to the clutch to engage the latter when displaced by the bar, and a mechanical connection between said push-plate and the movable shear, adapted upon the descent of the shear to cause the push-plate to recede therefrom.

5. In a power-shears, the combination of a driving-shaft, a clutch for coupling the movable shear to said shaft, and a push-plate in the path of feed of the bar being operated

- upon, connected to the clutch to engage the latter when displaced by the bar, a head-block carrying said push-plate, a longitudinal sliding bar to which said head-block is connected, and a connection between said bar and the movable shear adapted upon the descent of the shear to slide the bar longitudinally and cause the push-plate to recede from the shear.
6. In a power-shears, the combination of a driving-shaft, a clutch for coupling the movable shear to said shaft, and a push-plate in the path of feed of the bar being operated upon, connected to the clutch to engage the latter when displaced by the bar, a head-block S carrying said push-plate, a longitudinal sliding bar S' having a recess S², and an inclined cam-arm B' engaging said recess and fixed to the movable shear, whereby during the descent of the latter a thrust is communicated through said arm to said slide-bar to carry the head-block and push-plate away from the shears.
7. In a power-shears, the combination of a driving-shaft, a clutch for coupling the movable shear to said shaft, a push-plate R in the path of feed of the bar being operated on having a sliding plunger or frame, mechanical connections between said push-plate and clutch to engage the latter when displaced by the bar, the same consisting in part of a push-bar R², and a lever T guiding the end of said push-bar, holding it normally in line with said plunger and adapted by throwing the lever to carry it out of line therewith, and thereby throw the automatic clutch-operating mechanism out of action.
8. In a power-shears, the combination with a movable shear-head, a laterally-movable table V arranged to receive and support the bar to be cut as the latter is fed between the shears, and mechanism for operating said table adapted on the descent of the shear to move back the table from under the section of bar that is cut off by the shears to permit the latter to fall.
9. In a power-shears, the combination of movable shear-head B, sliding table V, arranged to support the bar to be cut as it is fed between the shears, and an elbow-lever 50 connection between said table and shear-head consisting of a rock-shaft V' extended parallel to the direction of feed of the bar to be cut, having an arm V² engaging said table and an arm V³ engaged by said shear-head, whereby upon the descent of the shear-head the table is caused to slide out from under the section of bar that is cut off.
10. In a power-shears having a driving-shaft, a clutch for coupling the movable shear 60 to said shaft, and a push-plate in the path of feed of the bar being operated on for automatically tripping the clutch, a clutch-engaging mechanism comprising a restraining-pawl j, a lever Q for rocking said pawl to release it and engage the clutch, and mechanical connections between said lever Q and the push-plate, combined with a hand-lever U for tripping the clutch manually, and an arm U² connected to it and acting against the lever Q, whereby said latter lever may be operated to release the clutch either from the push-plate or said hand-lever U.
11. In a power-shears, the combination with a roller-table having continuously-revolving rollers for feeding the bar to be operated upon to the shears, of a clamp having opposite jaws relatively movable to grip the bar between them to retard its feed, and an operating-lever connected to said clamp by which the operator may at will close the clamp upon the bar to arrest the latter.
12. In a power-shears, the combination with a roller-table having continuously-revolving rollers for feeding the bar to be operated upon to the shears, of a clamp I consisting of a fixed jaw I', and a movable jaw I², arranged on opposite sides of the path of travel of the bar to grip the bar between them, and an operating-lever N connected to said movable jaw I² to move it toward the fixed jaw, whereby the operator may at will close the clamp upon the bar to arrest the latter.
13. In a power-shears, the combination with a roller-table having continuously-revolving rollers for feeding the bar to be operated upon to the shears, of a clamp I consisting of a fixed jaw I', and a movable jaw I² formed on a slide s, with a transverse slideway for guiding said slide in its movements to keep the two jaws parallel, an operating-lever N, and a connecting-link s' joining it to said slide.
14. In a power-shears, the combination with a roller-table for feeding the bar to be operated upon to the shears, of a clamp I consisting of a fixed jaw I', and a movable jaw I² with transverse slideways for guiding the latter in its movement to hold it parallel to the fixed jaw, and a movable guide-bar P joined at one end to a fixed part and connected at the other end to said movable jaw, whereby it moves with the latter and guides the bar to be operated upon between the two jaws of the clamp.
15. In a power-shears, the combination with a roller-table for feeding the bar to the shears consisting of rollers geared together and revolving in the same direction, of a pressure-roller n mounted over the terminal roller k' of the roller-table, gearing for driving the roller n at the same speed as the rollers of the table but in the opposite direction, a movable frame o carrying said roller, a tension device for pressing said frame down, to cause said roller to grip the bar being fed, and an operating-lever N connected to said frame to raise it and free the bar.
16. In a power-shears, the combination with a roller-table for feeding the bar to the shears consisting of rollers geared together and revolving in the same direction, of a pressure-roller n mounted over the terminal roller k' of the roller-table, gearing for driving the

roller *n* at the same speed as the rollers of the table but in the opposite direction, a movable frame *o* carrying said roller, a clamp *I* for gripping the bar to retard its feed, and an operating-lever *N* connected to said frame *o*, and clamp *I* to simultaneously lift the pressure-roller free from the bar and to close the clamp against the bar.

17. In a power-shears or analogous machine, the combination with the driving-shaft, clutch and clutch-drum, of a brake for arresting the latter when the clutch is released consisting of jaws *g g* carrying brake-shoes engaging opposite sides of the rim of said drum, right and left nuts carried by said jaws, and a right-and-left-threaded oscillatory shaft *h* engaging said nuts, and a connection between said shaft and the clutch-operating mechanism for.

oscillating said shaft upon engaging or disengaging the clutch.

18. In a power-shears or analogous machine, the combination with the driving-shaft and clutch, of a clutch-operating mechanism comprising a tripping device, a falling bar *K* formed with a block *K'*, a lever-arm entering said block, and a sliding block movable in a transverse recess in said block *K'*, and formed with a socket receiving the rounded end of said lever-arm.

In witness whereof I have hereunto signed my name in the presence of two subscribing witnesses.

FRANK M. LEAVITT.

Witnesses:

GEORGE H. FRASER,
CHARLES K. FRASER.
